UNITED STATES PATENT OFFICE.

JOHN A. SECOR, OF BROOKLYN, NEW YORK.

DESIGN FOR A FRAME FOR EXPLOSIVE-ENGINES.

SPECIFICATION forming part of Design No. 27,037, dated May 11, 1897.

Application filed March 8, 1897. Serial No. 626,554. Term of patent 14 years.

To all whom it may concern:

Be it known that I, JOHN A. SECOR, a citizen of the United States, residing in the city of Brooklyn, county of Kings, State of New York, have invented and produced a new and original Design for Explosive-Engine Frames, of which the following is a specification, reference being had to the accompanying drawings, which form a part hereof.

10 My invention relates to a design for an explosive-engine frame, said frame comprising a base and intermediate part and a top cylinder, as shown in the accompanying drawings, in which—

15 Figure 1 is a view in elevation of an engine-frame which embodies my design. Fig. 2 is a view of the same in elevation, as seen from a point of view ninety degrees from the point of view of Fig. 1. Fig. 3 is a diagrammatic

20 plan view on the plane indicated by the line 3 3 of Figs. 1 and 2.

In the drawings the engine-frame is shown as a whole, in which 1 is the base, 2 is the intermediate portion, while the portion between

25 a and b is the top or cylindrical portion of the frame, which constitutes the leading feature of my design. As shown, this top part

from a to b is of a cylindrical appearance, with an enlargement e at the upper end and flaring buttresses f at the lower end, which merge into the sides of the cylindrical portion above referred to, springing from the flat surface g, substantially square in shape, and having a wavy or scalloped outline. This top part, already described, is superimposed upon four slender and substantially cylindrical pillars h h, one at each corner or lobe of the surface g, and these pillars in turn rest upon the lower portion or pedestal c d, which is of generally rectangular outline when seen either in elevation or in plan, with an ogee profile. When seen from one side, a bar or plate i appears to bridge the space between the pillars h h nearest the eye, and rods j j diverge from such pillars to the base or lower portion c d. 45

I claim—

The design for a frame for an explosive-engine, substantially as shown and described.

This specification signed and witnessed this 5th day of March, A. D. 1897.

JOHN A. SECOR.

In presence of—

ANTHONY N. JESBERA,
ANDREW H. SCOBLE.
